UNITED STATES PATENT OFFICE.

CHRISTOPHER R. JAMES, OF JERSEY CITY, NEW JERSEY.

CUT-OFF VALVE.

SPECIFICATION forming part of Letters Patent No. 425,176, dated April 8, 1890.

Application filed February 12, 1889. Serial No. 299,682. (No model.)

To all whom it may concern.

Be it known that I, CHRISTOPHER RETALICK JAMES, a subject of the Queen of Great Britain and Ireland, and a resident of Jersey City, in the county of Hudson and State of New Jersey, have invented certain new and useful Improvements in Automatic Variable Cut-Off Valves, of which the following is a specification.

10 The object of my invention is to introduce certain improvements in automatic variable drop cut-off appliances for regulating the supply of steam to engine-cylinders, and also improvements in the means of exhausting 15 from the same, whereby considerable saving will be effected in the cost of construction and also in the running expenses of the engines to which they are applied.

Hitherto cut off attachments have been 20 made to act through the influence of the governor upon the eccentrics and inlet-valves in such a manner that any undue wear of the parts causes an alteration in the initial supply of steam, and the ports have generally 25 been placed at unnecessarily long distances from the inlet and outlet valves, respectively, which is attended with more or less loss on that account. These defects my improvements are designed to remedy.

30 The novel features of my invention consist in the improved contrivances of separate and distinct mechanism for controlling the admission of the live steam through cut-off appliances, in the first place, and appliances for 35 afterward admitting it to and exhausting from the cylinder, both acting in unison with the engine, but quite independently of each other.

Having thus stated the character of my 40 improvements, I will now proceed to describe the mode of application by reference to the accompanying drawings, in which like letters refer to the same parts.

Figure 1 is a side elevation with the steam-chest cover removed, mainly representing the cut-off devices, but also showing some of the apparatus for controlling the inlet and exhaust. Fig. 2 is a transverse section through one of the cut-off valves. Fig. 3 is a horizontal section showing the position of the cylindrical cut-off valves in the steam-chest and

the mode of admitting steam to the cylinder. Fig. 4 is an enlarged view of one of the cut-off valves in sectional elevation on line *x x* of Fig. 6, together with devices illustrating 55 the manner of operating the same. Fig. 5 is an enlarged transverse section of the steam-chest and part of the cylinder, side view of the cut-off valve, and end view of the inlet and exhaust slide-valve, and showing openings through which the steam enters the cut-off valve; Fig. 6, a horizontal section on line *y y*, Figs. 4 and 5. Fig. 7 is a detail in transverse section through the steam-chest and exhaust-cavity of the inlet and exhaust valve. 60

G G are the cylindrical cut-off valve-casings situated in the steam-chest E, which extends the whole length of the cylinder and includes the ports at both ends. These valve-casings are open at the top and bottom, and 70 also in the center, as shown, so as to give ample area for the steam to be admitted. Each casing is composed of two rings cast on a face, which comes in contact with the back of the slide-valve P. (See Figs. 2, 3, 5, and 6.) 75 These casings are held in position by the rod p and the set-screws L N. The pressure of the steam keeps them up to the slide-valve P. They have ports 2, admitting steam to the slide-valve, and a groove 1 around the inside 80 of each ring of the valve-easing and connecting with the ports 2, which balances the valves as to the back-pressure of the steam when cut off, and thus prevents undue friction. 85

The cut-off valves consist of duplex skeleton ring-pistons I I, fitted to slide in the casings G G, respectively. Their stems a pass through packing-glands h, and have the cut-off lifters C, firmly fixed thereto by means of 90 set-screws 3, or it may be by keys or other suitable means. They are guided by set-screws 3, working in slots n in standards Q. The valves are raised and opened by the rocking beam U, and the lifting-paws R, acting 95 on the lifters C, said beam being connected to the eccentric-rod J and arm 4 by rods T and S, and said valves drop and close by gravity. They are balanced as to the live steam by the circulating of the same through the rings. 100

B represents cut-off slides free to move on the valve-stems a, but under control of the gov-

or nor W, being connected therewith by rod t, arms m and e, and shaft X, said arms m being connected to slides B at O, suitably to actuate them in right lines. The shaft X is supported in suitable bearings Z Z. The pawls R are moved upward and open the cut-off valves in unison with or prior to the opening of ports 5 by the slide-valve independently of the governor. The slide-valve P, attached to eccentric-rod at f, and controlling the inlet of the steam to and exhaust from the cylinder A, is of novel construction, being made sufficiently long to control both the ports 5, located at the extreme ends of the cylinder. It is made with live-steam passages 7 for admission of steam, and also with suitable exhaust-openings 6, whereby the exhaust-steam can be conducted away to the exhaust-port 8 through the same directly from the ends of the cylinder. This arrangement affords facilities for working with as little clearance as possible, and simplifies the cylinder construction.

Having now generally described the different parts of my invention and the portions of the engine to which they are affixed, as shown in the accompanying drawings, I will proceed to describe what takes place when the engine is in motion. Suppose a portion 30 of the load to be taken off the engine, then the natural tendency will be to accelerate the speed; but such acceleration causes the governor-balls to be thrown out farther by reason of the increased centrifugal force exerted, by which means the rod t is depressed, and, as will be seen, such action will lower the cut-off slides B, because these slides are free to move on the valve-stems a and advance the inclined surfaces relatively to the 40 pawls R; therefore the latter will be thrown off the lifters C at an earlier part of the stroke, and consequently the quantity of steam admitted will be reduced, for the reason that when the hollow piston-valves I I 45 are down both ports in the cut-off cylinder are covered by their respective rings, and thus prevent any more steam from entering until they are again lifted. The cut-off cylinders G G are situated in the steam-chest E, and through these all the steam is supplied 50 to the engine in the direction of the arrows, Figs. 4 and 5. The quantity of steam supplied is thus governed by these cut-off valves; but the time of entering and exhausting from 55 the cylinder is controlled by the slide-valve P only. By this improved cut-off I insure the uniform initial entry and exhaust as well as of the steam, no matter at what speed the engine may be traveling nor what may be the 60 point of cutting off, for the reason that the governor has nothing to do with the times of admitting steam to the cylinder and exhausting the same, but only with the quantity so admitted.

65 I claim as my invention—

1. The combination, with the slide-valve, of

the drop cut-off valves in stationary cases, along which the slide-valve moves, and connected with the eccentric through the lift and drop mechanism automatically variable as to 70 the dropping by the governor, substantially as described.

2. The combination, with the slide-valve directly connected with the eccentric-rod, of the drop cut-off valves in stationary cases 75 along which the slide-valve moves, and connected with the said eccentric through the lift and drop mechanism, automatically variable as to the dropping by the governor, substantially as described. 80

3. The combination, with the slide-valve directly connected with the eccentric-rod, of the drop cut-off valves in stationary cases along which the slide-valve moves, the rocking beam, and lifters also directly connected with 85 the eccentric-rod, and the lifter-tripping slides, automatically variable by the governor, substantially as described.

4. The combination, with the drop cut-off valves in stationary cases along which the 90 slide-valve moves, of the rocking beam and lifters connected with the eccentric-rod, and the lifter-tripping slides on the valve-stems connected with the governor through the arms, rock-shaft, and rods, substantially as de- 95 scribed.

5. The combination, with the steam-chest and slide-valve, including the cylinder-ports at both ends of the cylinder, and the slide-valve, having live-steam passages to the cylinder-ports, of the balanced piston drop cut-off valves in stationary cases seated on the slide-valve in the steam-chest coincident with 100 said passages, respectively, substantially as described. 105

6. The combination, with the steam-chest and slide-valve, including the cylinder-ports at both ends of the cylinder, and the slide-valve, having live-steam passages to the cylinder-ports and exhaust-passages alternately connecting both cylinder-ports with the individual exhaust-port, of the balanced piston drop cut-off valves seated on the slide-valve, coincident with said live-steam passages, respectively, substantially as described. 110 115

7. The combination, with the steam-chest and slide-valve, including the cylinder-ports at both ends of the cylinder, and the slide-valve, having the live-steam passages to the cylinder-ports, of the balanced piston drop cut-off valves, seated on the slide-valve in the steam-chest, coincident with the live-steam passages, respectively, and having the cases coupled together and with the steam-chest by the connecting-rod and adjusting-screws, 120 125 substantially as described.

8. The improved drop cut-off valve, consisting of the combined vertical cylindrical case, having middle and end inlet-openings, bearing-face, and two outlet-passages through 130 the bearing-face, and the duplex ring-pistons, substantially as described.

9. The improved drop cut-off valve, consisting of the combined vertical cylindrical case having middle and end inlet-openings, bearing-face, two outlet-passages through the bearing-face, and balancing-grooves coincident with the outlet-openings, and the duplex ring-pistons, substantially as described.

Signed at Jersey City, in the county of Hudson and State of New Jersey, this 11th day of February, A. D. 1889.

CHRISTOPHER R. JAMES.
